UNITED STATES PATENT OFFICE.

DURELL O. PEASE, OF HAMPDEN, MASSACHUSETTS.

CARDING MACHINE.

Application filed January 21, 1921. Serial No. 438,826.

To all whom it may concern:

Be it known that I, DURELL O. PEASE, a citizen of the United States, residing at Hampden, in the county of Hampden and 5 Commonwealth of Massachusetts, have invented certain new and useful Improvements in Carding Machines, of which the following, taken in connection with the accompanying drawings, is a full, clear, and 10 exact description.

My invention relates to an apparatus for the manufacture of rovings from asbestos or other flocculent fibre and it has for its object to provide an improved construction 15 of a carding machine whereby such rovings may be produced in a practical, efficient and inexpensive manner. Owing to the lack of sufficient tensile strength in fibres of flocculent material to withstand alone the necessary 20 operations to form them into rovings or yarns it is customary to make a combination with a supporting or core yarn of cotton or other material to give this additional strength.

25 My invention consists of the novel means and arrangement of parts of a carding machine for producing rovings, which will be hereinafter fully described and pointed out in the claim.

30 In the accompanying drawings Figure 1 is a sectional elevation of the delivery end of a finisher carding machine showing my improvements together with the condenser and roving spool winding means, the framing of the card and supports of the condenser rolls being omitted. Figure 2 is a 35 plan view of Figure 1. Figure 3 is a side elevation showing the driving means of my improvements. Figures 4 and 5 are longitudinal sectional views of the sliver supporting roll and core thread guiding roll respectively.

In carrying out my invention I make use 40 of a finisher carding machine comprising a main carding cylinder 1 of usual construction provided with card clothing from which the carded sliver is taken off by a doffer 2 of extra large diameter provided with either a series of rings of card clothing 3 separated by narrow rings of leather or other smooth material or as an alternative construction I prefer to make use of narrow strips of thin polished steel 4 fastened at one end to a stationary rod 5 supported by 45 brackets 6 fixed to the card sides 7. The steel strips superimposed on the surface of

the doffer extend below the contact point of the doffer and cylinder and are held in position by weights 8. By this construction the surface of the doffer at point of contact 60 with cylinder presents alternate spaces of card clothing and dividing strips by means of which the sliver is deposited in strips on the doffer and is removed therefrom by the action of an oscillating comb 9 of well 65 known construction. As the sliver delivered by the comb is lacking in tensile strength sufficient to withstand subsequent operations I provide additional strength to each strip of sliver by means of a core thread 10 of 70 cotton, or other material. These threads are drawn by the action of rub rolls 11 and 12 over a guide roll 13 and a sliver supporting roll 14 each provided with annular grooves, the center lines of which coincide with the 75 center line of the spaces of card clothing on the doffer. The rolls 13 and 14 revolve in bearings (not shown in drawings) fixed to the card sides. Rotary motion is imparted to the rub rolls and grooved rolls by suitable 80 gearing from the doffer, which is driven in the usual manner from the cylinder. The guide roll 13 is so placed that each sliver as it is combed from the doffer falls onto its respective supporting thread 85 and being supported thereby passes into the rub aprons 15 of usual construction where the sliver and thread are agglomerating together into a common mass in the form of a roving and wound on a spool 16 in frictional contact with the drum 17 which has a rotary motion imparted by a train of gears from the doffer gear 18, driving pulley 19, belt 20 and driven pulley 21 on shaft of 90 drum 17. 95

I am unaware that anyone has ever made use of a pair of annular grooved rolls such as I have adopted, for carrying the sliver and its supporting thread, in machines for forming rovings from flocculent material. 100 In carrying this part of my invention into effect I find the best results are obtained by forming the annular grooves in rolls 13 and 14 with wide openings and rounded bottoms of a diameter less than the width of 105 the strip of sliver. This construction tends to more thoroughly consolidate the sliver and its supporting thread together before being acted on by the condenser.

What I claim is:—

In a finisher carding machine having means whereby the sliver is delivered from

the doffer in narrow strips, the combination with said means of a supporting thread for each strip of sliver, a roll provided with an annular groove for each supporting thread, a second annular grooved roll for consolidating each sliver and its supporting thread, condenser rub-aprons for ag-

glomerating each thread and its sliver into a roving and means for operatively actuating the mechanism. 10

In testimony whereof, I have signed this specification.

DURELL O. PEASE.
